UNITED STATES PATENT OFFICE.

EDWARD SELDEN TOWNSEND KENNEDY, OF LARCHMONT, NEW YORK.

DESIGN FOR A STEAM-BOILER SETTING.

SPECIFICATION forming part of Design No. 26,804, dated March 23, 1897.

Application filed February 8, 1897. Serial No. 622,553. Term of patent 14 years.

To all whom it may concern:

Be it known that I, EDWARD SELDEN TOWNSEND KENNEDY, a citizen of the United States, residing at Larchmont, in the county of West-
5 chester and State of New York, have invented a certain new and useful Design for Steam-Boiler Settings; and I do hereby declare the following to be a full, clear, and exact description of the invention, such as will
10 enable others skilled in the art to which it appertains to make and use the same.

In the accompanying drawings, Figure 1 represents a front elevation of a steam-boiler setting embodying my design. Fig. 2 repre-
15 sents a sectional plan view thereof.

The leading features of my design consist in the upper section, presenting one surface of substantially cylindrical contour surmounted by another surface of substantially cyl-
20 drical contour, but smaller than the first, and a

lower section of general semicylindrical contour at the back and substantially rectangular at the front.

In the drawings, F is the lower surface of the upper section of generally cylindrical 25 contour. G is the upper surface of the upper section, also of general cylindrical contour, but smaller than the surface F, and H is the lower section of general semicylindrical contour at the back and substantially rectangular 30 at the front.

What I claim is—

The design for a steam-boiler setting, substantially as shown and described.

In testimony whereof I affix my signature 35 in presence of two witnesses.

EDWARD SELDEN TOWNSEND KENNEDY.

Witnesses:

JOHN HERRON WILLIAMSON,
HENRY SUMNER SWAIN.
